(57) **CLAIM**

The ornamental design for a segmented light fixture with wall mount, as shown and described.

DESCRIPTION

FIG. 1 is a perspective view, from the top, of a first embodiment of a segmented light fixture with wall mount in accordance with the new design;

FIG. 2 is a front view thereof;

FIG. 3. Is a rear view thereof;

FIG. 4 is a left side view thereof, with the right side being a mirror image;

FIG. 5 top view thereof;

FIG. 6 is a bottom thereof.

FIG. 7 is a perspective view, from the top, of the wall mount of the segmented light fixture in Embodiment 1 in accordance with the new design;

FIG. 8 is a perspective view thereof, from the top;

FIG. 9 is a perspective view thereof, from the bottom;

FIG. 10 is a front view thereof;

FIG. 11 is a rear view thereof;

FIG. 12 is a top view thereof, with the bottom being a mirror image; and,

FIG. 13 is a right side view thereof, with the left side being a mirror image.

The broken lines shown in the drawings are for the purpose of illustrating portions of the segmented light fixture with wall mount that form no part of the claimed design.

1 Claim, 8 Drawing Sheets
